ABSTRACT OF THE DISCLOSURE

An elongated body journaled within an air and liquid fuel passage for rotation about an axis extending transversely through the central portion of the passage and transversely of the body centrally intermediate its opposite ends. The ends include portions tending to rotate the body in one direction in response to flow of an air-fuel mixture through the passage. A baffle plate is provided in one side of the passage upstream of the body for deflecting at least a portion of the mixture to the other side of the passage.

This invention relates to a novel and useful liquid fuel atomizing attachment adapted to be utilized in conjunction with an internal combustion engine. The attachment of the instant invention includes a rotary body adapted for journaled support within an air and fuel inlet passage with the body being mounted for rotation about an axis extending transversely of the passage and adapted to impact with liquid fuel droplets moving through the passage and also cause turbulence within the passage so as to more completely atomize and vaporize the liquid fuel.

The body of the attachment is in the form of an elongated panel and includes portions at its opposite ends which are perforated and adapted to more completely atomize droplets of liquid fuel passing through the associated air and fuel inlet passage.

The atomizing attachment of the instant invention is operatively associated with the corresponding liquid fuel and air passage in a manner such that the rotational speed of the body of the attachment will increase as the flow of air and fuel through the passage increases.

The main object of this invention is to provide an atomizing attachment for operative association with an internal combustion engine and which will function to more finely atomize droplets of liquid fuel passing through the associated intake passage.

Another object of this invention is to provide an attachment for an internal combustion engine which will, by enabling a more finely atomized liquid fuel and air mixture to be supplied to the internal combustion engine, operate as a means to afford for more complete combustion of the air and fuel mixture in the combustion chambers of the associated engine thereby rendering the exhaust of the combustion engine less likely to contribute to smog conditions.

Yet another object of this invention, in accordance with the preceding objects, is to provide an atomizing attachment which, by providing a more completely atomized air and liquid fuel mixture to the associated inlet passage and affording more complete combustion of the air and fuel mixture in the associated combustion chambers, enable the associated internal combustion engine to propel the vehicle powered thereby a greater distance on a given amount of fuel.

A final object of this invention to be specifically enumerated herein is to provide an atomizing attachment

2

which will conform to conventional forms of manufacture, be of simple construction and automatic in operation so as to provide a device that will be economically feasible, long lasting and relatively trouble free in operation.

5 These together with other objects and advantages which will become subsequently apparent reside in the details of construction and operation as more fully hereinafter described and claimed, reference being had to the accompanying drawings forming a part hereof, wherein like numerals refer to like parts throughout, and in which:

10 FIGURE 1 is a fragmentary vertical sectional view taken through a portion of an air and fuel inlet passage of an internal combustion engine and illustrating the atomizing attachment of the invention operatively associated with the air and fuel passage;

15 FIGURE 2 is a fragmentary vertical sectional view taken substantially upon the plane indicated by the section line 2—2 of FIGURE 1;

20 FIGURE 3 is an enlarged fragmentary horizontal sectional view taken substantially upon the plane indicated by the section line 3—3 of FIGURE 1;

25 FIGURE 4 is a further enlarged fragmentary vertical sectional view taken substantially upon the plane indicated by the section line 4—4 of FIGURE 1; and

FIGURE 5 is a fragmentary sectional view taken substantially upon the plane indicated by the section line 5—5 of FIGURE 4.

30 Referring now more specifically to the drawings the numeral 10 generally designates a conventional form of internal combustion engine including an intake manifold 12 and a carburetor 14. The carburetor 14 has an air and fuel passage section 16 extending therethrough and the outlet end of the section 16 is registered with an air and fuel passage section 18 extending through the intake manifold 12. The sections 16 and 18 comprise portions of the air and fuel inlet passage of the internal combustion engine and it is to be noted that the carburetor 14 includes a mounting flange portion 20 by which the carburetor 14 is removably secured to the manifold 12 by means of any suitable fasteners (not shown), a suitable somewhat resilient and deformable gasket 22 being disposed between the opposing surfaces of the mounting flange 20 and the intake manifold 12.

45 The atomizing attachment of the instant invention is generally designated by the reference numeral 24 and includes a mounting frame 26 defined by a pair of generally parallel panel-like arms 28 including oppositely directed flange portions 30 on one pair of corresponding ends, the free ends of the flange portions 30 being disposed between adjacent layered plies of the resilient gasket 22.

50 An axle member 32 including diametrically reduced opposite end portions 34 is supported from the lower ends of the arms 28 for rotation relative thereto, the end portions 34 being rotatably received through suitable apertures 36 provided therefor in the arms 28. In addition, an anti-friction washer 38 is disposed on each end portion 34 inwardly of the associated arm 28 and a retaining washer 40 is mounted on each end portion 34 outwardly of the corresponding arm 28 and secured in position thereon by means of a suitable pin 42 removably passed through the corresponding washer 40 and the associated end portion 34.

55 A rotatable body generally referred to by the reference numeral 44 is provided and includes a central sleeve 46 journaled on the mid-portion of the axle member 32 between the arms 28. Spacer sleeves 48 are provided on the opposite end portions of the axle member 32 between the corresponding end portions of the sleeve 46.

60 65 A rotatable body generally referred to by the reference numeral 44 is provided and includes a central sleeve 46 journaled on the mid-portion of the axle member 32 between the arms 28. Spacer sleeves 48 are provided on the opposite end portions of the axle member 32 between the corresponding end portions of the sleeve 46.

70

and the associated anti-friction washer 38. The rotatable body 44 includes a pair of panel-like members 50 similar in configuration and secured to opposite side portions of the sleeve 46 by means of suitable welding 52. The panel-like members 50 are reversed end to end relative to each other and are disposed in generally parallel relationship. Further, a pair of spacer elements 54 are secured between each pair of adjacent ends of the members 50 and remote end portions of the members 50 include laterally outwardly directed and curved terminal end portions 56 defining air impact surfaces for imparting rotation to the rotatable body 44 in response to rapid movement of air through the sections 16 and 18, the end portions 56 being suitably apertured as at 58 and the other end portions of the members 50 also being suitably apertured as at 60 in a similar manner.

The mounting frame 26 of the attachment 24 includes a pair of oppositely opening U-shaped brace members 62 and 64 which rigidly interconnect the ends of the arms 28 adjacent the flange portions 30 and a baffle plate 66 including a base flange portion secured between the inner surfaces of the arms 28 adjacent the flange portions 30 and an inclined flange portion 70 projecting outwardly of one side of the mounting frame 26 acts as an air baffle to deflect portions of the air passing through the section 16 from one side of the latter to the other.

The baffle plate 66 comprising the flange portions 68 and 70 laterally deflects the air passing through the right hand side of the section 16 as seen in FIGURE 2 of the drawings toward the left sides of the sections 16 and 18. In addition, it will be noted that the terminal end portions 56 are curved in such a manner that the rotatable body 44 will rotate in a counterclockwise direction as viewed in FIGURE 2 of the drawings. Thus, the baffle 66 supplements the action of the terminal end portions 56 and acts to further increase the counterclockwise rotation of the rotatable body 44 as illustrated in FIGURE 2 of the drawings by deflecting some of the movement of the air through the right hand portion of the section 18 over to the left hand portion thereof.

The free ends of the terminal end portions 56 are of sawtooth configuration as at 72, see FIGURE 5, and this sawtooth configuration and the apertures 58 and 60 as well as the high rotational speed of the rotatable body 44 in response to rapid movement of an air and liquid fuel mixture passing through the sections 16 and 18 serve to cause portions of the rotatable body 44 to strike and thus break up droplets of liquid fuel being carried in the airflow passing through the sections 16 and 18. In addition, rotation of the body 44 at high speeds causes a turbulence in the adjacent area of the section 18, which turbulence further acts to break up droplets of liquid fuel remaining in the flow of air passing through the section 18.

It may therefore be readily seen that the atomizing attachment of the instant invention is operative to more finely atomize droplets of liquid fuel carried by an air-stream moving through the sections 16 and 18. Therefore, the internal combustion engine 10 will function more efficiently by developing more power on a given amount of fuel and enable the associated vehicle to travel greater distances on the same amount of fuel. In addition, this more efficient operation of the associated combustion engine will greatly reduce those byproducts of combustion which support the formation of smog.

Although a specific embodiment of the invention has been described and illustrated herein, it is to be noted that the rotatable body 44 may be constructed of any suitable material such as metal or plastic or combination of materials with sufficient strength and pliability to be formed into numerous shapes and designs adapted to be received in various different air and fuel passages. In addition, the sleeve 46 may be rotatable upon the shaft or axle member 32 or fixed in position thereon with the axle member 32 rotatably supported from the support arms

5 28. Of course, any suitable material may be utilized in the construction of the sleeve 46 and the shaft or axle member 32. In addition, although the rotatable body 44 has been illustrated and described herein as constructed of a plurality of components secured together to form an integral unit, the various portions of the rotatable body may be separable and the body may form any suitable number of generally radially extending blade-like members such as the opposite end portions of the panel-like members 50. Also, it is to be noted that a pair of side by side contra-rotating rotatable bodies could be utilized in lieu of the single body 44 and that the mounting frame 26 may also be constructed of any suitable material. Finally, the atomizing attachment of the instant invention may be utilized in many similar environments other than in conjunction with the air and fuel passages of an internal combustion engine and for the purpose of providing a more desirable and complete mixture of any suitable combination of fuel and oxidizer. In this regard, if the atomizing attachment is not used in conjunction with an air and fuel passage of an internal combustion engine, an external power supply or driving motive force may be operatively coupled to the rotatable body 44 in order that the latter may be utilized in the desired manner without relying upon a rapid fluid flow there past for imparting rotation thereto.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

35 What is claimed as new is as follows:

1. In combination with a passage member defining an air and fuel passage, mounting means mounted in said passage, a rotary liquid fuel impacting and atomizing body journaled from said mounting means in said passage 30 with the axis of rotation of said body extending transversely of and generally centered in said passage, said body being elongated and extending transversely of said axis, the latter being disposed generally centrally intermediate the opposite ends of said body, said body defining a medial plane and including a transverse dimension extending along said axis considerably greater than the thickness of said body, and air deflecting baffle plate means supported from said mounting means and including portions disposed in one side of said passage upstream 40 from said axis and inclined relative to the longitudinal center line of said passage operative to deflect at least portions of the air and fuel mixture passing through said passage from said one side thereof to the other side thereof and thereby cause rotation of said body in one direction in response to movement of said mixture through said passage.

2. The combination of claim 1 wherein said body is defined by a pair of panel-like members spaced on opposite sides of the medial plane of said body.

60 3. The combination of claim 2 wherein the opposite ends of said panel-like members are perforated.

4. The combination of claim 2 wherein said medial plane of said body and said axis generally coincide.

65 5. The combination of claim 4 wherein said body includes a pair of generally parallel panel-like members disposed on opposite sides of said axis, the opposite end portions of said panel-like members being perforated.

70 6. The combination of claim 1 wherein said passage member includes a pair of end abutted passage defining sections defining said passage member, said mounting means includes a pair of generally parallel support arms including oppositely directed flange portions on one pair of corresponding ends disposed between opposing end faces of said sections, said body being journaled from and

disposed between the other pair of corresponding ends of said arms.

7. The combination of claim 6 wherein said baffle plate is generally planar and is stationarily supported from said mounting means laterally of said axis and disposed in a plane generally paralleling said axis but inclined at least slightly relative to a line extending between said baffle plate and said axis, said baffle plate being supported from said one pair of corresponding ends of said arms.
